(57) CLAIM

The ornamental design for a handbag, as shown and described.

DESCRIPTION

FIG. 1 is a front perspective view of a handbag showing my new design;

FIG. 2 is a front view thereof;

FIG. 3 is a left side view thereof;

FIG. 4 is a right side view thereof;

FIG. 5 is a top view thereof;

FIG. 6 is a front perspective view of the handbag shown in FIG. 1 with the ring and chain in a different position;

FIG. 7 is a front view thereof;

FIG. 8 is a back view thereof;

FIG. 9 is a left side view thereof;

FIG. 10 is a right side view thereof; and,

FIG. 11 is another view of the handbag in FIG. 6.

The broken lines showing of portions of the body of the handbag in the drawings shows unclaimed subject matter. The bottom of the handbag forms no part of the design.
